CAKE OF SOAP

Alejo Rodriguez, Astoria, N. Y.

Application January 23, 1957, Serial No. 44,578

Term of patent 14 years

(Cl. D73—1)

Fig. 1 is a top plan view of a cake of soap, showing my new design;

Fig. 2 is a front elevational view of the same;

Fig. 3 is a vertical sectional view taken on the line 3—3 of Fig. 1; and

Fig. 4 is a bottom view of Fig. 1.

I claim:

The ornamental design for a cake of soap, substantially as shown.
